UNITED STATES PATENT OFFICE.

GEORGE D. KRATZ, OF AKRON, OHIO, ASSIGNOR TO THE FALLS RUBBER COMPANY, OF CUYAHOGA FALLS, OHIO, A CORPORATION OF OHIO.

SWIMMING TUBE AND VALVE CAP THEREFOR.

Application filed March 9, 1922. Serial No. 542,246.

To all whom it may concern:

Be it known that I, GEORGE D. KRATZ, a citizen of the United States, and a resident of Akron, county of Summit, and State of Ohio, have invented a new and useful Improvement in Swimming Tubes and Valve Caps Therefor, of which the following is a specification, the principle of the invention being herein explained and the best mode 10 in which I have contemplated applying that principle, so as to distinguish it from other inventions.

The present invention relates to a swimming tube and more particularly to the valve 15 and valve cap construction and means for covering the same to prevent injury from the extending valve and valve cap. The use of an inner tube for automobile tires as a swimming tube has been increasing, but the 20 extending valve stem is dangerous, and the present tube is provided with means for covering the valve stem and cap to prevent injury to the swimmer or swimming suit. To obtain a satisfactory tube it has been found 25 necessary to use a tube which will contain air under rather high pressure necessitating the use of a satisfactory valve of the "Schrader" type which makes it necessary to inflate the tube from a pump or other 30 source of fairly high pressure. This type of valve necessitates a rather long valve stem of metal and it is to protect the user from such a stem that the present valve cap and covering means have been designed. To the 35 accomplishment of the foregoing and related ends, said invention, then, consists of the means hereinafter fully described and particularly pointed out in the claims.

The annexed drawing and the following 40 description set forth in detail certain mechanism embodying the invention, such disclosed means constituting, however, but one of various mechanical forms in which the principle of the invention may be used.

45 In said annexed drawing:—

Fig. 1 is a perspective view of my tube with cap and cover in place; Fig. 2 is a sectional view through the tube cap and cover when the tube is inflated; Fig. 3 is a sectional view through the valve cap; Fig. 4 is a perspective view of the valve cap with the rubber cut away and showing in section; and Fig. 5 is a perspective view of the valve stem end.

55 The present device comprises a circular

endless tube 1 of a convenient size to fit under the arms of a bather, which tube is provided with a valve stem 2 provided with the usual or modified "Schrader" type of valve commonly used in inner tubes for 60 automobile tires and the like.

As best shown in Fig. 2, the valve stem is mounted within the tube being held in place between two nuts or washers 3 which have complementary corrugated rubber contact- 65 surfaces 4 to form an air tight joint. The extending outer end 5 of the valve stem is threaded to receive the usual metal valve cap 6, but this end 5 extends beyond the surface of the tube only sufficiently to allow a 70 cap 7 to be threaded thereon, the main body of the valve stem extending inwardly of the tube.

The valve cap 7 has its upper end formed into a series of tongues 8 which are rebent 75 down adjacent the upper edge of the cap forming loops and this metal cap 7 is vulcanized into a hood or covering 10 of soft rubber. The cap may be otherwise shaped or imbedded in the hood or covering ma- 80 terial in any suitable manner so that the cap cannot be pulled free. This hood 10 is hemispherical in general shape but formed with a concave under surface 11 which is adapted to fit snugly adjacent the curved surface of 85 the tube, thus covering the valve stem and cap with resilient material unlikely to scratch or injure the bather, although when the tube is inflated the friction between the hood and the tube is sufficient to prevent the 90 accidental unscrewing of the cap. As an additional protection for the user and to prevent accidental unscrewing of the hooded cap, a band or ring 12 of rubber is employed which is wide enough to extend to both sides 95 of the hooded cap and this band encircles the tube and is adapted to be slipped over the cap into the position shown in Figs. 1 and 2 where it will remain due to the air pressure within the tube and thus there is no 100 sharp projection which can scratch the user, or catch in bathing clothes and tear the same.

The entire tube is simple to construct and to inflate and will of course be made in such sizes as to suit children as well as 105 adults. The entire outer surface is smooth and the cap is so covered that no sharp projection is formed and the band prevents accidental unscrewing or displacing of the valve cap. This cap is securely fixed in the 110

rubber hood and the cap is suitable for use with other types of articles where it is desired to cover a valve stem.

Other modes of applying the principle 5 of my invention may be employed instead of the one explained, change being made as regards the mechanism herein disclosed, provided the means stated by any of the following claims or the equivalent of such 10 stated means be employed.

I therefore particularly point out and distinctly claim as my invention:—

1. In a swimming tube, the combination 15 of a circular endless tube, provided with a valve stem, a hooded cap for said valve stem, and a band of rubber slidably mounted on said tube and adapted to cover said valve stem and cap when said tube is inflated.
2. In a swimming tube, the combination 20 of a circular endless tube, provided with a valve stem, said stem being mounted within said tube and having an outwardly extending threaded end, a hooded valve cap adapted 25 to engage with said threaded valve stem end and cover the same, and a band of rubber slidably mounted on said tube and adapted to cover said cap when said tube is inflated.
3. In a swimming tube, the combination 30 of a circular endless tube, provided with a valve stem, said stem being mounted within said tube and having an outwardly ex-

tending threaded end, a hooded valve cap comprising an interiorly threaded cap provided with a hood of resilient material, said cap being adapted to engage with said extending valve stem and said hood being adapted to fit snugly against the tube to cover the metallic cap and stem, and a band 40 of rubber slidably mounted on said tube and adapted to cover said cap when said tube is inflated.

4. A valve cap for pneumatic swimming tubes, comprising a threaded metallic cap 45 adapted for engagement with a valve stem, and a hood of soft resilient material mounted over said cap and secured thereto.

5. A valve cap for pneumatic swimming tubes comprising a hemispherical hood of 50 soft rubber having a metallic valve cap embedded therein.

6. A valve cap for pneumatic swimming tubes comprising a hemispherical hood of 55 soft rubber having a concave lower face, and a metallic valve cap vulcanized therein.

7. A valve cap for pneumatic swimming tubes comprising a hemispherical hood of 60 soft rubber having a concave lower face, and a metallic valve cap provided with loops of metal on its top embedded in said hood and vulcanized therein.

Signed by me, this 6th day of March, 1922.

GEORGE D. KRATZ.
